UNITED STATES PATENT OFFICE.

HARRY E. FOURCHER, OF AUGUSTA, GEORGIA.

BICYCLE-LOCK.

1,204,753.

Specification of Letters Patent. Patented Nov. 14, 1916.

Application filed June 3, 1915. Serial No. 31,925.

To all whom it may concern:

Be it known that I, HARRY E. FOURCHER, a citizen of the United States, residing at Augusta, in the county of Richmond and State of Georgia, have invented a new and useful Bicycle-Lock, of which the following is a specification.

This invention relates to locks for bicycles, and other vehicles utilizing coaster brakes, 10 one of the objects of the invention being to provide a compact structure which, when in position, does not present an unsightly appearance and which, when in use, serves positively to hold the wheel of the vehicle 15 against rotation.

One of the objects of the present invention is to provide a lock, one member of which can be substituted for the fixed arm commonly employed in connection with 20 coaster brakes or can be fixedly mounted in any other suitable manner, while the opposed member of the lock can be integral with or attached to the hub of the wheel so as to rotate therewith whereby, when the 25 two members of the lock are in engagement with each other, the wheel is held securely against rotation upon its axle.

With the foregoing and other objects in view which will appear as the description 30 proceeds, the invention resides in the combination and arrangement of parts and in the details of construction hereinafter described and claimed, it being understood that changes in the precise embodiment of 35 the invention herein disclosed can be made within the scope of what is claimed, without departing from the spirit of the invention.

In the accompanying drawings the preferred forms of the invention have been 40 shown.

In said drawings:—Figure 1 is a side elevation of a portion of a vehicle wheel having a coaster brake with which the present 45 improvements are combined. Fig. 2 is a section on line A—B Fig. 1, the end portion of the wheel hub being shown in elevation. Fig. 3 is a transverse section through the lock and showing the tongue thereof in engagement with its keeper. Fig. 4 is a section 50 on line C—D Fig. 3. Fig. 5 is a similar view showing the relative positions of the tumblers when the wheel is unlocked. Fig. 6 is a section on line E—F Fig. 3, the 55 keeper being removed. Fig. 7 is a sectional perspective view of the barrels of the lock.

Fig. 8 is a detail view of a key for use in connection with the lock. Fig. 9 is an elevation of the lock used in connection with a hub in which notches are formed.

60

Referring to the figures by characters of reference 1 designates a portion of a wheel having combined with it a coaster brake structure indicated generally at 2. Coaster brakes of the standard types, such as the 65 "Corbin", "New departure" and "Morrow" require the use of an arm which is connected to a portion of the frame of the vehicle. It is designed, in the present instance, to substitute for said arm, an arm 3 70 similar in appearance to the usual arm but provided, along its inner face and close to but below the hub, with a lock casing 4 in the top portion of which is formed a longitudinal slot 5 having a side extension 6 75 shorter than the balance of the slot and forming a recess.

Fixedly mounted in one end portion of the casing 4, which casing is preferably cylindrical as shown, is a barrel 7 extending partly through the casing, this barrel being held against rotation in any suitable manner, as by means of a diametrically disposed pin 11. Another barrel 9 is mounted 80 for rotation within the casing and abuts against the fixed barrel 7, the two barrels 7 and 9 being provided with registering bores 10. The pin 11 extends across the bore in the barrel 7 while another pin 8 is secured in the barrel 9 and extends across 85 the bore therein, the two pins 8 and 11 being engaged by the ends of a torsion spring 12 which is housed at all times within the bores.

90 Recesses 13 are formed in the fixed barrel 9 at the inner end thereof and arranged in these recesses are springs 14 constantly bearing against the ends of tumblers 15.

The revoluble barrel 9 is provided on its periphery with a tongue 16 which, when in locking position, is seated within the recess 100 6 in the casing 4 but, when in unlocked position, is seated within the projecting portion of the slot 5. Barrel 9 is provided with one or more longitudinal passages 17 extending therefrom so that, when said passages 105 are brought into register with the recesses 13, the tumblers 15 can be seated therein automatically, thus coupling together the two barrels and preventing rotation of 110 the barrel 9 relative to barrel 7. When the parts are thus located the tongue 16 is

seated in the recess 6. Pins 19 are slidably mounted in the passages 17 and are adapted, when the barrels are locked together, to bear against the tumblers 15. Guard wings 20 are extended from the outer end of the barrel 9 and are spaced apart to form a slot 21 designed to receive a key 22 which can be of the form shown in Fig. 7 wherein parallel fingers 23 are provided and are adapted to be inserted into the passages 17 and to thus thrust the tumblers 15 out of the counterbores 18. It is to be understood that when it is desired to move the tongue 16 out of its locking position within the recess 6, the key 22 is to be inserted into the lock as described so as to thrust the tumblers 15 out of the counterbores 18. The barrel 9 is then rotated in a clockwise direction so as to twist the spring 12 and, when the tongue 16 is thus removed from recess 6 and brought into line with the extension of slot 5, the spring 12 thrusts on the barrel 9 and shifts it longitudinally so as to bring tongue 16 into the extension of slot 5.

With the parts thus positioned, when it is desired to shift the tongue 16 to locking position, it is merely necessary to push the barrel 9 inwardly against the action of coiled spring 12 so as to thus shift the tongue 16 out of the extension of slot 5. As soon as the tongue moves out of the extension of slot 5, the wound torsion spring 12 will rotate the barrel 9 so as to shift the tongue 16 into recess 6 and bring the passages 17 into register with recesses 13. Consequently the tumblers 15 will shift automatically into the passages 17 and thus lock the two barrels together.

Any suitable means may be provided for engagement by the tongue 16. For example, and as shown in Figs. 1 and 2, a ring 24 can be placed upon the hub of the wheel 1, this ring being provided in its outer side, with a desired number of notches 25 any one of which is designed to receive the tongue 16 when it is shifted to locking position. Ring 24 can be fixedly connected to the hub of the wheel in any desired manner. For example, it can be formed with fingers 26 having recesses 27 in the sides thereof, these fingers being interlaced with the spokes of the wheel.

Or, if preferred, the ring could be fastened by screws or the like to the hub. Another form of structure has been illustrated in Fig. 9 wherein, instead of providing a ring upon the hub, notches 28 are formed directly in the end of the wheel hub and a stationary cap 30 is fitted against said hub. This cap has a notch 31 in the bottom thereof adapted to receive tongue 16, the notches 28 being covered by cap 30 except when brought into register with notch 31.

For preventing accidental thrusting against the projecting end of the barrel 9 when the tongue 16 is in unlocked position, a nose or guard 29 is preferably extended from the arm 3 so as to project beyond the end of the barrel 9 and thus prevent objects from striking against the barrel accidentally.

What is claimed is:—

The combination with a notched revolvable member, of a fixed lock casing having a slot provided with a side recess, alining fixed and movable barrels within the casing, resilient means extending into both barrels and thrusting the movable barrel away from the fixed barrel, a locking element carried by the movable barrel and normally held by said resilient means, pressed against one end of the slot and out of the recess in the side of the slot, tumblers movably mounted in the barrels for holding the locking element in the recess and in one of the notches in the movable member, said tumblers being yieldingly pressed, and key actuated means for forcing the tumblers out of the movable barrel thereby to release the barrel, the resilient means within the barrel and which normally thrusts the barrels apart, operating to simultaneously rotate the movable barrel when released to remove the locking element from the recess and to thrust said movable barrel longitudinally to position the locking element against the end of the slot in the casing.

In testimony that I claim the foregoing as my own, I have hereto affixed my signature in the presence of two witnesses.
